UNITED STATES PATENT OFFICE

JOSEPH EGGERT, OF COLUMBUS, OHIO, ASSIGNOR TO THE JAEGER MACHINE COMPANY, OF COLUMBUS, OHIO, A CORPORATION OF OHIO

WATER TANK FOR CONCRETE MIXERS

Application filed July 10, 1931. Serial No. 549,861.

This invention relates to water tanks for concrete mixers and particularly to such as are used on truck mixers. One object of the invention is to provide improved means whereby a measured quantity of water can be withdrawn from the tank. Another object is to provide improved means for locking the water supply opening while discharging the water. Another object is to provide a tank 10 in which there is a separate chamber for a mixer flushing supply of water independent of the main supply, said separate chamber also having means for preventing water from being supplied thereto during its discharge. 15 Other objects will appear from the disclosure herein.

The invention is embodied in the example herein shown and described, the features of novelty being finally claimed.

20 In the accompanying drawings—

Figure 1 is a view in side elevation of the tank according to the invention applied to a tank mixer.

Fig. 2 is a view of the tank on a larger scale 25 partly in section, removed from the truck mixer.

Fig. 3 is a view looking at the right hand end of Fig. 2 with a portion of the end broken out showing some interior details.

30 Fig. 4 is a section on the line IV—IV Fig. 2 with some parts in full.

Fig. 5 is a plan view of the covers for the charging openings to the two compartments of the water tank.

35 In the views 10 designates a mixing drum shown as mounted to turn on a horizontal axis on a transporting truck. The mixing drum is of the species which mixes the concrete materials by rotation of the drum in one direction 40 and discharges by rotation in the opposite direction. Details of such a truck concrete mixer are shown in the application of Jaeger and Eggert, filed April 9, 1931, Ser. No. 528,806 and need not be described more particularly herein.

The tank for supplying water to the concrete materials within the drum includes the following parts, to wit: A cylindrical vessel or tank 11 is supported in an elevated position on the chassis forward of the front end of the 50 mixing drum 10. Said vessel is divided into a large and a small compartment by a vertical partition 12. The large compartment which supplies water for the concrete mixture in the drum communicates with the interior of the 55 mixing drum through a pipe 13 entering the axis of said drum. The smaller compartment for supplying flushing water communicates with the interior of the mixing drum through the same pipe 13, there being an external 60 cross pipe 14 connecting the discharges of the two compartments so that both lead into the mixing drum.

The discharge of the larger compartment is controlled by a valve 15 above the inlet of 65 the cross pipe 14 to the pipe 13; and the discharge of the smaller compartment as controlled by a valve 16, so that water may be discharged from either compartment without discharging it from the other. 70

The charging openings for the tanks at 17 and 18 are closed by covers 19 and 20 carried by a single arm 21 swinging on a handled stem 22. Said stem 22 is threaded at its lower end in a fixed nut 23 at the top of a pair of perforated ears 24; and said stem is limited in movement by a nut 25 on the lower end of the threaded portion of the stem. On the stem above the fixed threaded nut 23 is a coil spring 26 tending to lift the arm 21 against a fixed 75 stop nut 27 above the arm and the covers off their seats when the threaded stem is turned in the proper direction. When the arm 21 is so lifted it can, if not otherwise locked as hereinafter described, be turned on the stem 80 to remove the covers from above the charging openings.

The stem 16 carrying the valve 16 is long 85 and rests at its lower end in a cup 27 on the upper end of a threaded stem of a hand wheel 90

28 so that by turning said wheel in the proper direction said stem 16^a can be raised to lift the valve 16 off its seat to cause the discharge of water from the smaller compartment of the tank. When the hand wheel is turned 5 to raise the valve 16, and the cover at the top is closed, the upper end of the stem 16^a enters the hole 21^a in the arm to a sufficient extent to prevent the turning of the arm and the removal of the cover.

10 The stem 15^a of the valve 15 extends upward through the larger compartment of the tank to a guiding socket or hole 29 in the top of the tank.

15 Pivoted between the ears 24 is a lever 30 to the free end of which is attached one end of a link 31 having its other end pivotally connected with the end of a crank arm 32 on a shaft 33 that extends through a pipe to the exterior of the tank. At its external end the shaft 33 has a crank arm 34 for raising and lowering the valve 15 through the connections described with the stem of said valve. The weight of the lever 30, the valve rod and their 20 connections are supplemented by a spring 35 to aid in holding the valve 15 closed. The aforesaid connections can be made sufficiently loose to allow for curvilinear motions in places where such occur. The crank arm 34 is 25 supported in the opened and closed positions of the valve 15 by means of a pin 36 sliding in a tube and provided with handle for moving it against a spring 37 from a path of said crank arm 34 when it is shifted to open the 30 valve 15 or to permit the same to be closed.

35 Secured around the discharge of the larger compartment is an extensible conductor 38 made preferably of flexible rubber in corrugated or accordion form so as to be collapsible.

40 The conductor 38 is attached at its upper end to a metallic guide block sliding on the valve stem, said guide block provided with clamping means for engaging the upper end 45 of the conductor. Attached to the guide block is a pair of links 39 having their other ends connected with crank arms 40 on the end of a tubular shaft 41 (see Fig. 4) in the stationary housing shaft 42. Said tubular shaft 50 41 works around the valve operating shaft also within said housing shaft, and said tubular shaft 41 extends through the head of the tank, it being provided at its external end with an operating crank arm 43 provided 55 with a knob for conveniently moving it. Said crank 43 works over an arcuate strip 44 marked with a scale to indicate the height to which the accordion conductor is raised and therefore the quantity of water that can be 60 taken from a full tank compartment when raised to that position or the quantity of water that can be taken from the tank after prior known or given withdrawals.

65 Supported on the lever 30 is a headed pin 45 having its shank extended into a hole in

the top of the tank in line with the hole 21^b on the arm carrying cover 19 so that when the valve 15 is raised to discharge water the arm 21 cannot be operated to remove the cover of the charging openings to either the small or 70 large compartment. It will thus be seen that the tank cannot be charged with water when water is being withdrawn from either compartment of the tank.

75 A water glass can be provided for either or both compartments, such as shown at 46 so that the quantity of water in either tank may be observed at any time, it being important that means shall be provided whereby the contractor or his agent may keep check on the 80 workmen to prevent them from putting into the concrete mixer more or less water than the specifications call for.

85 47 designates an overflow pipe for fixing the quantity to be supplied to the larger compartment; and 48 is a baffle to prevent undue splashing or agitation of the water when the truck mixer is in transit over rough roads.

90 The forms of the parts can be changed without departing from the gist of the invention as claimed.

95 What I claim is:

1. Means for supplying water to a concrete mixer including a tank provided with a discharge opening to the mixer, a valve for said discharge, a collapsible conductor within the tank communicating with said discharge, and means external to the tank for moving said conductor to effect the removal 100 of the desired portion of water for the mixer 105 from the tank.

110 2. Means for supplying water to a concrete mixer including a tank provided with a discharge opening to the mixer, a valve for said discharge, a collapsible conductor within the tank communicating with said discharge and means external to the tank for moving said conductor to effect the removal of a desired portion of water for the mixer 115 from the tank, and means for latching said means in the opened position of said valve.

120 3. Means for supplying water to a concrete mixer including a tank provided with a discharge opening to the mixer, a valve for said discharge, a collapsible conductor consisting of a flexible tube within the tank communicating with said discharge, and means external to the tank for moving said conductor to effect the removal of the desired portion of water for the mixer from the tank.

125 4. Means for supplying water to a concrete mixer including a tank provided with a charging opening and a discharge opening, a closure for the charging opening and a valve for the discharging opening, means for actuating said valve at will to open the discharge and means actuatable by the valve 130

- to lock the charging closure when the discharge is opened.
5. Means for supplying water to a concrete mixer including a tank having two water containing compartments each having a charging and discharging opening and valves for the discharge openings, means for actuating either of said valves at will, closures for said charging openings, and means actuated by either valve for locking both
- 10 said closures in closing position.
6. Means for supplying water to a concrete mixer including a tank having two water containing compartments, each provided with a charging opening and each provided
- 15 with a discharging opening and a valve therefor, closure means for said charging openings and means for preventing the removal of either of said closures when one of said valves is opened to discharge water.
- 20 7. Means for supplying water to a concrete mixer, including a tank provided with a charging opening and a closure therefor, and a discharge opening to the mixer provided with a valve having a stem, means external of the tank for actuating said valve and stem, and means whereby said stem causes the locking of the closure of the charging opening when the valve is in open position.
- 25 8. Means for supplying water to a concrete mixer including a tank provided with a charging opening and closure means therefor, and a discharge opening to the mixer provided with a valve having a stem and means whereby said stem engages the closure means to lock the closure from removal when said valve is in open position.
- 30 9. Means for supplying water to a concrete mixer including a tank provided with a charging opening and closure means therefor, and a discharge opening to the mixer provided with a valve having a stem, said stem being movable independently of the
- 35 valve, means external to the tank for operating said stem and means whereby said stem engages the closure means to lock the closure from removal when said valve is in open position.
- 40 10. In water measuring and supply apparatus for concrete mixers, a receptacle; a supply conduit for said receptacle; a discharge conduit leading from said receptacle; and flexible extensible means for varying
- 45 the length of the intake portion of said discharge conduit for controlling the quantity of water it may discharge from said receptacle.
- 50 11. In water measuring and supply apparatus for concrete mixers, a receptacle; a supply conduit for said receptacle; a discharge conduit leading from said receptacle, having a flexible extensible intake extension; and means for longitudinally adjusting said
- 55 flexible extension to control the quantity of
- water said conduit may discharge from said receptacle.
12. In water measuring and supply apparatus for concrete mixers, a receptacle; a supply conduit for said receptacle; a discharge conduit leading from said receptacle; provided with a flexible pleated intake portion; and means for extending and contracting said pleated portion to control the quantity of water said conduit may discharge from said receptacle.
